United States Patent Office

Des. 218,056

Patented July 14, 1970

218,056

URN

Mary L. Urrutia, 4 Manhattan St.,
Jackson, N.J. 08527

Filed Sept. 24, 1969, Ser. No. 19,271

Term of patent 14 years

Int. Cl. D11—02

U.S. Cl. D35—3

FIG. 1 is a front elevational view of an urn showing my design, the rear view thereof is similar to the front view;

FIG. 2 is a top or plan view thereof;

FIG. 3 is a bottom view thereof; and

FIG. 4 is a sectional bottom view taken along the plane of line 4—4 in FIG. 1.

I claim:

The ornamental design for an urn, as shown and described.
